KNIFE-ADJUSTING MECHANISM FOR BARK-REMOVING MACHINES.

1,068,371.

Specification of Letters Patent. Patented July 22, 1913.

Application filed March 20, 1912. Serial No. 685,016.

To all whom it may concern:

Be it known that I, TRACY W. SIMPSON, of Grand Rapids and State of Michigan, have invented certain new and useful Improvements in Knife-Adjusting Mechanism for Bark-Removing Machines, of which the following is a specification.

My invention relates to bark removing machines, and particularly to improved mechanism for gaging the depth of cut of the bark removing knives.

In machines to which my invention is adaptable, the knife blades rest against the logs from which the bark is to be removed, and I shall show my invention applied to the machine disclosed in Patent No. 1,017,655, granted February 20, 1912, to Herbert L. Drake. In a machine of this patent, the knives are suspended from pivoted beams and rest against the logs, the beams being of sufficient weight to press the knives through the bark. It has been found in practice, however, that at certain times the weight will not be sufficient to force the knives entirely through the bark, and at other times the weight is too great and the knives will be forced into the body of the log. In the machine of the patent referred to, the blades are set at an angle with reference to the log axis, which angle is greater than the angle of pitch of the helical path of a point on the periphery of the log so that the bark besides being cut along the helical line is at the same time forced loose from the log. With such arrangement, if the knives are not forced entirely through the bark, the bark will be torn and will not be entirely removed. Again, if the blades are forced beyond the depth of the bark and into the log body, part of the log body will be forced off. It is desirable to have the knives cut entirely through the bark at all points of the log, but not to cut any deeper.

One of the important objects of this invention is therefore to provide gaging mechanism in connection with the blades so that the depth of cut can be regulated independently of the weight tending to force the blades through the bark, the weight acting on the blades being sufficient at all times to force the blade entirely through the bark and the gage mechanism then taking up the weight and preventing too deep cutting by the blade.

Another object is to provide simple adjusting mechanism for the gaging mechanism so that the depth of cutting can be quickly and accurately regulated during the operation of the machine.

The various features of my invention will be thoroughly understood by reference to the accompanying drawings which show the invention applied to a machine such as disclosed in the patent referred to.

In these drawings, Figure 1 is a plan view of the machine; Fig. 2 is an end elevational view thereof, and Fig. 3 is an enlarged sectional view through the blade and gaging plate, to illustrate the operation thereof.

Referring to the drawings, the machine shown comprises a carriage or truck 10 mounted on wheels 11 engaging the rails 12 of a track, the truck being adapted to reciprocate back and forth on said track. At one side this truck mounts bearing standards 13 which journal a shaft 14 carrying supporting wheels 15, a wheel being at each end of the truck. At its opposite side the truck supports sets of bearing standards 16 and 16' which journal a shaft 17, which between the standards 16 and 16' of each set carries a spur wheel 18. The spur wheels have key and slot connection with the shaft, so that the wheels are confined to rotate with the shaft, but may have longitudinal movement with reference thereto. One of the spur wheels 18 is opposite each of the supporting wheels 15, and these supporting wheels and spur wheels form between them a trough for receiving a log to be treated. The shaft 17 being rotated, the teeth or spurs 18' on spur wheels 18 engage with the log and cause rotation thereof.

Adjacent one end of the track a stationary frame 19 is provided, whose rear section 19' extends upwardly and terminates in a bearing box 20 for journaling one end of the main drive shaft 21, the opposite end of this shaft being journaled at the top of the bearing standard 22 arranged adjacent the opposite end of the track. The shaft 17 before mentioned is below and in front of the shaft 21, and its left end journals on the frame 19, while its right end journals in the standard 23 at the right end of the track. Adjacent the inside of the frame 19, shafts 21 and 17 carry gears 24 and 25 respectively which mesh with each other. Adjacent the

outside of the frame 19 the main shaft 21 carries the driving pulley 26 which may be connected by a belt with any suitable driving source. Adjacent the outer side of the frame 19 the shaft 17 carries a skew gear 27 which meshes with the skew pinion 28 mounted on the shaft 29 extending at right angles to shaft 17 and journaled at the outside of frame 19 in bearings 30 and 31. In front of and below the shaft 17 is the screw shaft 32 extending in a plane substantially midway between the planes of the shafts 17 and 14, the shafts 17 and 14 being substantially in the same horizontal plane. In a journal box 33 supported on frame 19 a short shaft 34 is journaled. This shaft at its inner end is connected with the screw shaft 32 by universal coupling 35 of any suitable construction. The left end of the shaft 34 terminates in a bevel friction pinion 36 which is adapted for engagement with either one of the friction beveled drive gears 37 and 38 journaled on the sleeve 39 mounted on shaft 29. Secured to the outside of the frame 19 is the bracket 40 in which pivoted at its elbow is the bell crank adjusting lever 43. The inner end of this lever forks over the sleeve 39, while the outer end of the lever is pivoted to a screw 44 which threads in a sleeve 45 journaled in the bearing extension 46 on bracket 40, the sleeve having a hand wheel 47. Upon turning of the hand wheel the bell crank lever will be swung correspondingly to cause shifting of the sleeve 39 and driving connection with the pinion 36 of either driving gear 37 or driving gear 38, the direction of rotation of the screw shaft 32 being thus adjustable. The screw shaft 32 threading through a lug 40 or a nut 48 secured to the carriage 10, the carriage with the log supported thereon may be moved in either direction on the track. As the carriage is moved over its track by the rotation of the screw shaft 32 the spur wheels 18 rotating with shaft 17 will cause rotation of a log L supported on the spur wheels and the wheels 15.

On both the carriage and the log supported thereon is mounted the mechanism for removing the bark from the log. This mechanism consists of one or more sets, each comprising transverse scraping and helical cutting mechanism. The cutting mechanism of each set comprises a blade 53 carried at the front end of a frame 54 which is pivoted at its rear end to the shaft 21. Each frame comprises blocks 55 pivoted to the shaft 21, and from which extend the bars 56 which terminate at their front end in a head 57. As shown each knife has extending from its rear end a threaded stud s, and at its front end the blade is pivotally suspended from a bolt 58 passing upwardly through the head 57 and secured by a nut 60, the blade being thus pivoted to the head 57.

Extending between the side bars 56 and secured thereto at an intermediate point is the cross piece 61 having a slot 62 through which extends the stud s of the blade to be engaged by the nut 63. The angularity of the knife with reference to the axis of the log can thus be regulated by swinging the blade about its front pivot and securing it in adjusted position by tightening of the nut 63. During cutting operation the blade rests on the log, the sharp edge of the blade cutting and penetrating the bark along a helical line. The log on the carrier, as has been explained, has combined bodily movement and axial rotary movement, and any point on the log will therefore describe a helix. The angle of pitch of this imaginary helix is preferably less than the angle at which the blade is set. With this arrangement not only will the bark be cut by the blade along a helical line, but the blade will act like a plow to exert lateral pressure against the helical band cut from the bark, so that the helical band is loosened from and deflected away from the log body.

In the machine of the patent referred to the weight of the knife supporting frames 54 was depended upon to force the cutting edges of the blades through the bark. It has been found, however, that at some time, as where the bark is thicker, the weight would not be sufficient to force the blades entirely through the bark, and at other points, as where the bark is thinner, the weight is too great and the cutting edge would sink into the log body. In both cases, the proper cutting and removal of the bark is interfered with. However, in accordance with my invention, gaging mechanism is provided which will insure proper cutting and proper removal of the bark at all times. As shown, a gage plate 70 is associated with each cutting blade, the plate being preferably suspended adjacent the blade to ride over the top of the bark so as to allow the cutting edge of the blade to cut entirely through the bark but no deeper, the weight of the knife supporting frames being made sufficiently great so that under all conditions it would be sufficient to force the cutting edge entirely through the bark. As soon as the cutting edge has passed through the bark, the gage plate will prevent deeper cutting and will take up the excess weight. The gage plate is preferably arranged to be vertically adjustable with reference to the blade to which it is applied and one way to accomplish this is to provide diagonal slots 71 in the gage plate for receiving bolts 72 extending from the blade. With this arrangement longitudinal movement of the gage plate will effect vertical adjustment thereof, and adjustment of the distance between the lower edge of the plate and the cutting edge of the blade. In order

to readily effect longitudinal adjustment of the plate an adjusting lever 73 is provided for each plate and pivoted between the bars 56 of the knife supporting frame as plainly shown in Fig. 2. The lower end of the lever pivots to a link 74 which has loose pivotal connection with a link 75 extending from one end of the gage plate, so that when the lever 73 is swung the plate will be longitudinally moved and vertically adjusted on the blade with reference to the cutting edge thereof.

To lock the parts in adjusted position, the lever 73 has a grip 76 pivoted thereto for controlling the coöperation of a detent 77 with a notched segment 78 secured to the frame 54. In the arrangement described, the gage plate 70 can be quickly and accurately adjusted even during operation of the machine and the proper depth of cut by the knives is assured.

As in the patent referred to provision may be made for raising the knife supporting frames 54 and as shown cables 79 extend from the ends of the frames and pass about a drum 80 mounted on a shaft 81, this shaft carrying a sprocket wheel 82 adapted for connection by belt 83 with a driving sprocket wheel 84 on the main driving shaft 21. Also, as in the patent referred to, scraping chain belts 85 may be provided for scraping off some of the bark at either side of the knives.

I do not of course desire to be limited to the precise form of gaging mechanism which I have shown, as other constructions would also embody the broad feature of my invention.

I claim the following:

1. In a bark removing machine, the combination of means for supporting a log, a knife supporting frame extending transversely of said log, a knife suspended from said supporting frame to engage with the bark on said log at an angle with its axis, the weight of said supporting frame causing said knife to be forced through the bark,

an abutment plate supported on said knife and having diagonal movement thereon, and setting mechanism mounted on said supporting frame and connected with said abutment plate to effect diagonal movement thereof to thereby gage the depth of cut on said bark by said knife. 50

2. In a bark removing machine, the combination of means for supporting a log, a knife supporting frame extending cross-wise of the log, a knife blade suspended from said frame to engage cross-wise with the bark on said log, the weight of said frame serving to force the knife blade into the bark, studs extending from said knife blade, an abutment plate having diagonal slots for receiving said studs and mechanism supported on said frame for effecting 65 longitudinal shift of said abutment plate and thereby vertical adjustment thereof to control the depth of cut by said knife blade.

3. In a bark removing machine, the combination of members for supporting a log, a 70 knife blade supported to engage with the bark on said log, and an abutment plate adjustable diagonally on said blade to be set to gage the depth of cut on said bark by said blade. 75

4. In a bark removing machine, the combination of means for supporting a log, a supporting frame, a knife blade pivoted at one end to said frame to be thereby adapted for lateral adjustment to any desired angle 80 with reference to the axis of the log, an abutment plate carried by said knife blade, and means carried by said supporting frame for effecting vertical adjustment of said plate on said blade to thereby adjust the 85 depth of cut by said knife, such adjustment of the abutment plate being independent of the lateral adjustment of the blade.

In witness whereof I hereunto subscribe my name this 18th day of March, A. D. 1912. 90
TRACY W. SIMPSON.
